UNITED STATES PATENT OFFICE.

DANIEL L. CHANDLER, OF AYER, MASSACHUSETTS, ASSIGNOR TO FITCHBURG BOBBIN CLEANING MACHINE CO., OF FITCHBURG, MASSACHUSETTS, A CORPORATION OF MASSACHUSETTS.

BOBBIN-CLEANING MECHANISM.

1,145,000.

Specification of Letters Patent.

Patented July 6, 1915.

Application filed October 26, 1914. Serial No. 868,642.

To all whom it may concern:

Be it known that I, DANIEL L. CHANDLER, a citizen of the United States, residing at Ayer, in the county of Middlesex and State 5 of Massachusetts, have invented a new and useful Bobbin-Cleaning Mechanism, of which the following is a specification.

This invention relates to mechanism for cleaning bobbins and particularly to the 10 parts for taking the material directly from the bobbins. It can be used with any desired mechanism for feeding the bobbins and for discharging them as well as for disposing of the lint after it is removed.

15 The principal objects of the invention are to provide simple mechanism that will effectually take the filling from bobbins of that type provided with circumferential grooves and more specifically to provide 20 acting mechanism for first loosening the tight portion of filling usually found near the butt of the bobbin and thereafter effectually taking all filling out of the grooves and from the remainder of the bobbin; also 25 to provide improved means for actuating the successive stripping and cleaning jaws; and especially to provide an improved form of 30 cleaning jaw which will effectually clean the above specified type of bobbin as well as all other ordinary types.

The invention also involves other features of construction as will appear hereinafter.

Reference is to be had to the accompanying drawings in which—

Figure 1 is a side view of a bobbin stripping machine showing a preferred form of this invention applied thereto with the parts in the position assumed at the end of the 40 stroke; Fig. 2 is a similar view showing the parts at the beginning of the stroke; Fig. 3 is an enlarged side view showing the parts in the position shown in Fig. 1 and illustrating details of the jaws and connected 45 parts; Fig. 4 is a plan of the same showing the racks in section; Fig. 5 is a sectional view on the vertical line 5—5 of Fig. 3; Fig. 6 is an end elevation of the cleaning 50 jaws showing their supporting studs; Fig. 7 is a side view of the cleaning jaws as shown in full lines on Fig. 6; Fig. 8 is a plan of one of the cleaning jaws; Fig. 9 is a sectional view of the same on the line 9—9 of Fig. 8, and Fig. 10 is a side elevation of 55 the cams for operating the jaws.

Although the principles of this invention can be applied to many types of bobbin stripping machines they are especially adapted to that form shown in my application for patent, Ser. No. 822,698, filed 60 March 5, 1914. Accordingly I have shown the invention herein as applied to that construction.

The bobbins are fed into position to be stripped by means of a rotary wheel 23 having pins 24 thereon for the bobbins and the stripping mechanism is operated by a crank 40, link 41 and slide 42 connected with the link. This slide traverses over a guide 43 mounted on the frame 10 of the machine. It 70 will be understood that the wheel is operated in any desired way to bring each bobbin to be stripped into horizontal position and that the slide 42 is moved back and forth on the guide 43 for the purpose of 75 stripping the bobbins, the slide being provided with bobbin stripping means. This bobbin stripping means constitutes the subject matter of this application. The bobbin is held from motion during the stripping 80 action by a stud 35.

The slide 42 is provided with opposite openings 44 therethrough across which pass two studs 45 and 46. On each of these studs are pivoted arms for use in removing the 85 filling from the bobbin. Two arms 47 are shown, each provided with a steel knife jaw 48. Each of these arms is free to turn on its stud and on them are gear segments 49^a and 49 respectively. These two gear segments mesh with each other. One of them, 90 49, meshes with the teeth of a reciprocating rack 50. This rack has a projection 51 on the back by which it is reciprocated in a manner that will appear later. One 95 of these arms is provided with a stud 52 thereon for limiting the approach of the arms to each other. It will be obvious that this rack can be reciprocated to turn the arm and jaws from the position shown in 100 dotted lines in Fig. 5, in which they are housed within the openings 44 of the slide 42, to the position shown in full lines in the same figure where they approach the bobbin and engage the filling so as to remove it upon being forced along the bobbin. The other two arms 53 are operated by 105 gear segments in the same way, a rack 54 being provided for that purpose. Each one is provided with a cleaner jaw head 110

57 projecting to one side for receiving the jaws proper. In this case, they are made for the purpose of engaging the filling in the grooves of the bobbin a plurality of 5 times during the passage of the jaws over them and thus rolling the filling out of the grooves when it shows a tendency to stick. For this purpose each of these heads is made of substantially semi-cylindrical form 10 and is provided with a plurality of movable jaws 55 therein. In this case three of these are shown in each head. They are secured in position by means of a pin 56 which is fixed to the head. The three jaws 55 are 15 provided with perforations 58 larger than the pin to permit a reciprocation of the jaws. They are guided in slots in the heads so that they can move radially. Each of the outer two jaws 55 is forced inwardly 20 by a spring 59 while the middle one is forced inwardly by a flat spring 60 which also engages the head 57 and is secured to it for the purpose of forcing the head itself toward the bobbin as well as the central jaw. 25 The inner edge of each jaw is provided with teeth 61 for the purpose of engaging the threads. A preferred way of making these heads and jaws is to take a piece of metal and turn it up to a cylindrical form with 30 a flange 63 on the end and bore it out at the center. Then it is cut in two through the center and slots cut into it in any desired way for the purpose of receiving the jaws 55. The jaws are then inserted and 35 the two members which have been cut apart are then temporarily secured together. A tap is forced in through them to form threads on the inner surfaces of the heads and jaws. These threads constitute the 40 teeth 61 and serve to engage the filling when the device is used. The diameter on which these teeth are curved, that is the diameter of the tap, is made larger than the largest diameter of the spindle of the bobbin that 45 has to be engaged by them. Thus the middle portions of the teeth will engage the filling but the corners will not dig into the bobbin. As shown, the surfaces are rounded and cut off at the points 64 and 64^a 50 for the purpose of convenience in applying the device to the machine and permitting it to be housed within the opening 44 and folded back into the dotted line position shown in Fig. 6, and for clearing the bobbin 55 at the ends of the teeth.

For the purpose of operating the two racks 50 and 54 and their projections 51 and 65 the frame 10 of the machine is provided with cam tracks. The upper cam track is 60 used to engage the projection 51 and thus operate the slide 50. For this purpose it is shown as comprising a straight groove 67 bounded at the bottom by a solid projection 68. At the end of this projection 68 65 is a slanting groove 69 communicating with

the groove 67 at the top. Below the projection 68 is another groove 70 parallel with it and communicating with the groove 69. A spring-pressed switch 71 yields to permit the projection 51 to rise up an incline 70 72 and to guide it up on a ledge 73 when the slide is moving back. But when the slide moves forward this switch receives the projection 51 and forces it up into the groove 67. The top of the groove 70, or 75 rather the bottom of the projection 68, constitutes positive means for preventing the knife jaws moving apart too far on the operative stroke. The other cam is of a similar nature. It comprises a groove 74 which, at the beginning, is closed by a spring-pressed switch 75 to force the projection 65 up into a parallel groove 76 above a central projection 77. It also has a ledge 78 and an inclined passage 79, the latter being similar to the inclined passage 69. A second spring-pressed switch 80 is used for the purpose of holding the projection 65 up during the forward stroke of the slide and guiding it on the ledge 78. It then springs 85 up and lets it come back down the inclination 79. Each rack has a spring 82 for yieldingly holding it down.

From the description which has been given the operation will be clear. The bobbins are brought around into horizontal position in any desired way and the machinery is so timed that when a bobbin is in the proper place the slide 42 can move back toward the bobbin support. As it moves 95 back both projections 51 and 65 are supported in the upper slots 67 and 76 respectively. Just before the slide reaches the end of its stroke the upper projection 51 encounters the inclined groove 69 and is 100 ready to drop back into the slot 70. At the same time the projection 65 rides out on the switch 80 to the ledge 78 and as the parts start back they are in this position, as shown in Fig. 2. This allows the knife 105 jaws to close and keeps the cleaning jaws open for a while. Now as the slide moves back the knife jaws are in contact with the filling on the bobbin and force off the filling which usually is found at the large end of 110 the bobbin. This is why these jaws are made of steel and arranged to engage the bobbin only at its largest diameter. As the slide continues to move these jaws remain in the same position and although they would 115 remove any filling sticking up from the surface of the bobbin, they do not again come close enough to the bobbin itself to remove all filling therefrom. It has been found in practice that they do not under these circumstances remove the filling from the grooves shown in the bobbin. As the slide moves forward from the position shown in 120 Fig. 2 the projection 65 is permitted to come down the incline 79 into the slot 74 130

after the knife jaws have moved along the bobbin a short distance. In this way the cleaning jaws are brought into contact with the bobbin and they are pressed against the 5 bobbin by the pressure of the springs 59 and 60 throughout the remainder of the travel of the slide in that direction. Thus although the arms and heads are kept in constant position the jaws 55 are held in contact 10 with the bobbin, or rather the filling thereon, by spring pressure throughout the rest of the travel. The action of these cleaning jaws is important. The teeth with which each is provided rub over the surface on 15 which any thread lies in succession. Consequently they tend to roll over such a thread if it does not yield immediately. It has been found in practice that with three of these jaws on each side, each provided 20 with a plurality of threads or teeth, the filling will actually be drawn out of the grooves and effectually removed from the bobbins. Toward the end of the stroke in this direction the projection 65 comes out from under 25 the switch 75, but remains in the same position. At the same time the projection 51 moves up under the switch 71 and is held in a half-open position. As the slide starts back both these projections are lifted and 30 the jaws are opened wide shortly after the slide starts to move back toward the bobbin support.

Although I have illustrated and described 35 only a single embodiment of the invention and shown it as applied only to a single type of cleaning machines, I am well aware of the fact that the invention can be carried out in other forms and applied to many types of bobbin cleaning machines without 40 departing from the scope thereof as expressed in the claims. Therefore I do not wish to be limited in these respects, but

What I do claim is:—

1. In a bobbin cleaner, the combination 45 with a support for a bobbin, of means adapted to move along a bobbin while on the support, and two sets of jaws carried by said means for operating on the bobbin to remove the filling therefrom.

50 2. In a bobbin cleaner, the combination with a support for a bobbin, of means adapted to move along a bobbin while on the support, and two sets of jaws carried by said means, one behind the other and adapted to 55 operate on the same bobbin during a single stroke of said means.

3. In a bobbin cleaner, the combination 60 with a support for a bobbin, of means adapted to move along a bobbin while on the support and two sets of jaws carried by said means for removing the filling therefrom, one of said sets of jaws having knife edges 65 for engaging the filling and stripping it off at the large end of the bobbin and the other set of jaws having a plurality of teeth for

successively engaging each particle of filling remaining.

4. In a bobbin cleaner, the combination of means adapted to move along a bobbin, two sets of jaws carried by said means to remove 70 the filling therefrom, means for positively holding one of said sets of jaws in constant position during the travel of said member, and means for yieldingly holding the other set of jaws against the filling on the bobbin. 75

5. In a bobbin stripping machine, the combination of a slide movable longitudinally with two pairs of jaws carried by the slide, the jaws of one of said pairs having knife edges for engaging the filling and removing 80 it from the large end of the bobbin during the first part of the stroke, and the other pair of jaws being spring-pressed and adapted to engage the bobbin throughout its length. 85

6. In a bobbin stripping machine, the combination with a support for a bobbin and a slide movable longitudinally, of two pairs of jaws carried by said slide, means whereby at the beginning of the stroke of the slide one 90 pair of jaws is first caused to move toward the large end of the bobbin to remove the filling therefrom and held in that position during the remainder of the stroke, and means whereby the second pair of jaws is 95 caused to engage the bobbin in the same position after the first pair of jaws has passed.

7. In a bobbin stripping machine, the combination with a support for a bobbin, and a slide movable longitudinally, of two pairs of jaws carried by said slide, means whereby at the beginning of the stroke of the slide one pair of jaws is first caused to move toward the large end of the bobbin to remove the filling therefrom, and means whereby the second pair of jaws is caused to engage the bobbin after the first pair of jaws has passed, and yielding means for holding the second pair of jaws in engagement with 105 the bobbin during the remainder of the stroke. 110

8. In a bobbin stripping machine, the combination of a reciprocable slide, a rack mounted thereon and movable transversely, a pair 115 of jaws pivoted on the slide, each having a gear segment connected therewith, said gear segments meshing with each other and one of them with the rack, and means for operating the rack as the slide reciprocates. 120

9. In a bobbin stripping machine, the combination of a reciprocable slide, a rack mounted thereon and movable transversely with respect to the direction of motion of the slide, a pair of jaws pivoted on the slide, each having a gear segment thereon, said gear segments meshing with each other and one of them with the rack, a projection on the back of the rack, and a double cam track for receiving said projection and oper- 130

ating the slide, said cam track having means for guiding the projection from one part to the other at the end of the stroke.

10. In a bobbin stripping machine, the combination of a head with jaws movably mounted in said head and located in position to engage the side of a bobbin for stripping the filling therefrom, the inner surface of said head and jaws having a continuous 10 set of teeth thereon.

11. A jaw mechanism for a bobbin stripping machine comprising a pair of semi-cylindrical heads having an axial passage therethrough for receiving a bobbin, each 15 head having perforations therethrough arranged radially, a jaw in each of said perforations slideable along the same, and yielding means for forcing said jaws inwardly.

12. In a bobbin stripping machine, the combination with a pair of semi-cylindrical heads each having a longitudinal row of perforations therein extending radially, a jaw loosely mounted in each perforation, each jaw having a series of transverse teeth 25 on its inner face, and yielding means for forcing said jaws inwardly.

13. In a bobbin stripping machine, the combination of a pair of heads having a space between them for receiving the bobbin, 30 each head having a series of loosely mounted jaws arranged longitudinally thereon and adapted to project through the inner face of the head, each jaw being provided with a series of transverse teeth on its inner end.

35 14. In a bobbin stripping machine, the

combination of a pair of heads having a space between them for receiving the bobbin, each head having a series of loosely mounted jaws arranged longitudinally thereon and 40 adapted to project through the inner face of the head, the inner surfaces of the heads and jaws being concave, and teeth thereon constituting parts of screw threads.

15. A bobbin stripping member for a machine of the class described, comprising a head having a concave inner face and provided with a series of cavities, a series of jaws mounted loosely in said cavities and 45 adapted to move inwardly beyond said concave face, each jaw having also a concave face and provided with transverse teeth.

16. A bobbin stripping member for a machine of the class described comprising a head having a concave inner face and provided with a series of cavities, a series of jaws mounted loosely in said cavities, said head having a longitudinal rod therein passing through said jaws and each jaw having a hole therethrough for the rod, said holes 50 being larger than the rod to permit play of the jaws, and springs for forcing the jaws 60 inwardly.

In testimony whereof I have hereunto set my hand, in the presence of two subscribing 65 witnesses.

DANIEL L. CHANDLER.
